METAL FIXTURE FOR TYPEWRITER DESKS

Martin Fox, Chicago, Ill., assignor to The Seng Company, Chicago, Ill.

Application April 27, 1950, Serial No. 158,575

3 Claims. (Cl. 312—27)

1

This invention relates to pedestal desks of the type in which one of the pedestals is provided with a compartment for housing a typewriter and having means for supporting the typewriter in such manner that it may be moved from retracted position in the compartment to extended writing position, and more particularly it relates to an improved swinging mechanism for the typewriter platform and a new arrangement of counter-balancing springs.

The primary object of the invention is to provide a simple, rugged and dependable mechanism for extending and retracting the typewriter platform of the desk, the mechanism being so arranged that the platform swings in a smooth continuous arc from retracted position to writing position, and makes its final motion into writing position in an upward and rearward direction.

Another object of the invention is to provide a mechanism in which there is sufficient forward component to the initial movement of the platform from writing position that the platform may be latched in writing position by engagement of a spring latch bar with an upwardly open U-shaped notch.

Still another object is to provide a mechanism in which the counter-balancing spring is stretched and in a "dead center" position when the platform is retracted so that after a slight forward pull on the platform the spring assists the forward swing thereof substantially all the way to writing position.

The invention is illustrated in a preferred embodiment in the accompanying drawings, in which: Fig. 1 is a side elevation of a typewriter desk with the typewriter platform in writing position; Fig. 2 is a plan view thereof with the desk top removed, the platform being in retracted position, and being shown in interrupted lines in writing position; Fig. 3 is a fragmentary plan view similar to Fig. 2, but on an enlarged scale; Fig. 4 is a section taken as indicated on the line 4—4 of Fig. 2; Fig. 5 is a fragmentary sectional view of the latch and latch-trip mechanism; Fig. 6 is a fragmentary broken front elevational view of the latch and latch-trip mechanism; Fig. 7 is a sectional view similar to Fig. 4, but showing the mechanism with the typewriter platform in a position between retracted and writing positions; Fig. 8 is a sectional view similar to Fig. 7 with the platform in writing position; and Fig. 9 is an enlarged fragmentary sectional view taken as indicated along the line 9—9 of Fig. 7.

In the embodiment illustrated, a conventional pedestal desk has upright frame members 10 pro-

2

viding legs, which are joined by panel members 11 surmounted by a top 12. A typewriter compartment 13 has a bottom wall 14 and a door member indicated at 15.

5 A pair of tracks 16 have mounting brackets 17 at their forward ends which are screwed to two of the front upright frame members 10 of the desk, and the rear ends of the tracks are fastened to two rear upright frame members with screws 18.

10 A carriage 19 is provided with a front pair of anti-friction rollers 20, and a rear pair of rollers 21, engaged on opposite sides of the tracks 16. Front bell cranks 22 are pivoted to the carriage at 23, and rear bell cranks 24 are pivoted to the carriage at 25.

15 A pair of brackets 26, to which is bolted a typewriter platform 27, are pivotally connected to the ends of the bell cranks 22 and 24 at 28 for parallel movement; and a pair of parallel side links 29 are pivotally connected to the other ends of the bell cranks at 30.

20 A pair of guide links 31 are pivotally connected to the side links 29 at 32, and are also pivotally connected at 33 to a pair of upstanding lugs 34 at the front end of the tracks 16. In assembling the mechanism within the typewriter compartment of a desk, it is necessary that the guide links 31 be fastened to the side links 32 after the carriage is on the tracks, and this is preferably accomplished by employing studs as the pivots 32 and securing the studs through the side links 29 and guide links 31 by means of frusto-conical, corrugated, annular spring grippers 32a which frictionally grip the shanks of the studs.

25 An arched cross bar 35 spans the carriage 19 above the rear bell cranks 24, and is fastened to the carriage at 36. A transverse bar 37 extends between the rear bell cranks 24 below the pivots 25 and in a position such that tension counter-

30 balancing springs 38 which are fastened to the arched cross bar 35 and to the cross bar 37 are in a dead center position when the carriage is in its most retracted position—that is, the line of the springs 38 passes substantially directly through the line of the pivots 25 in said position.

35 Due to this dead center arrangement of the counter-balancing springs 38, the springs are in their most elongated condition when the mechanism is fully retracted, and only a slight forward movement of the platform is required to put the counter-balancing springs 38 into operation to assist in the forward and upward movement of the typewriter platform 27.

40 As best seen in Fig. 5 a pair of latch assembly plates 39 are fastened inside the upper front

50

corners of the typewriter compartment by means of screws 40. A pair of swinging latch arms 41 are pivoted on the latch plates 39 at 42 and are drawn downwardly against stop pins 43 by tension springs 44 which are fastened to the swinging arms 41 and to spring lugs 44a. A latch bar 45 extends transversely between the swinging arms 41. When the typewriter platform 27 is elevated toward the writing position shown in Fig. 8, the latch bar 45 strikes cam surfaces 52 at the rear of the platform brackets 26, pivoting the latch arms 41 against the tension of spring 44, and in writing position the latch bar engages a pair of upwardly open notches 46 adjacent the cam surfaces 52 to retain the platform in writing position. Mounted at the rear of the typewriter platform 27 is a bifurcated bracket 47 in which a latch-trip 48 is pivoted on a rivet 49. The forward portion of the latch-trip 48 is a finger piece 50, and the rear portion 51 thereof projects beneath the latch bar 45 when the platform is in writing position. Thus, in order to disengage the latch bar 45 from the upwardly open notches 46 of the platform brackets it is merely necessary to depress the finger piece 50 of the latch-trip 48 so as to elevate the swinging latch arms 41 against the tension of the spring 43.

The operation of the device will be readily understood. When it is desired to withdraw the typewriter from the compartment 13, the door 15 is opened, the forward end of the typewriter platform 27 is grasped and the platform is pulled forward. The motion of the platform 27 and carriage 19 causes the guide link 31 to rotate about its pivot 33, thus pivoting the bell cranks 22 and 24 about their pivots 23 and 25, and beginning the elevation of the platform 27 in a smooth arc about the pivots of the bell cranks. As soon as the counter-balancing springs 38 are off their dead center position, the rotation of the bell cranks and elevation of the platform 27 is assisted by the tension of the counter-balancing springs, which continue to exert a lifting force throughout substantially the entire travel of the platform 27—enough so that the momentum of the platform is almost sufficient to complete the travel to writing position shown in Fig. 8 without further effort on the part of the operator. As the platform reaches writing position, the latch bar 45 comes into action as previously described to latch the platform 27 in writing position. The initial travel of the platform from writing position has sufficient forward component that the frictional engagement between the latch bar and the rear upright surface of the notch 46 is adequate to maintain the platform in writing position.

The operation of the latch-trip has been previously described. The mechanism is extremely

safe for the operator, because if the latch bar is accidentally disengaged from the upwardly open notches 46, the typewriter platform can swing downwardly only a short distance before the increasing tension of the counter-balancing springs 38 becomes great enough to hold the platform in equilibrium.

The foregoing detailed description is given for clearness of understanding only and no unnecessary limitations should be understood therefrom, as modifications will be obvious to those skilled in the art.

I claim:

1. A metal fixture for a typewriter desk in which a platform carrying a typewriter may be extended from a compartment and swung up to writing position, said fixture comprising: tracks for attachment to the walls of the compartment; a carriage antifrictionally journaled on said tracks and provided at each side with a front bell crank and a rear bell crank; brackets for a typewriter platform pivotally mounted on one end of each of said bell cranks for parallel movement; side links connecting the other ends of the bell cranks; a pair of guide links connecting said side links to positions near the front ends of said tracks; and a latch mechanism for releasably securing the platform brackets in writing position.

2. A metal fixture as specified in claim 1 wherein in the platform brackets have upwardly open notches, the latch member is a transverse bar mounted on a pair of swinging arms and is spring urged downwardly into engagement with the open notches, and a latch-trip adapted to be supported by the platform brackets in such a position as to have a portion projecting beneath said transverse bar in writing position, said latch-trip being pivotable to elevate the transverse bar and free it from said notches.

3. A metal fixture as specified in claim 1 in which the platform brackets have upwardly open notches and the latch mechanism comprises a pair of latch plates adapted to be mounted on the walls of the typewriter compartment, a pair of swinging arms on said latch plates, a transverse bar mounted on said arms to engage said upwardly open notches, and spring means urging said bar downwardly into engagement with the notches.

MARTIN FOX.
